UNITED STATES PATENT OFFICE.

JOHN ARNOLD STREUN, OF BOWIE, TEXAS.

APPARATUS FOR CLEANING COTTON.

Specification of Letters Patent. Patented Feb. 19, 1918.

1,256,742.

Application filed June 12, 1918. Serial No. 103,118.

To all whom it may concern:

Be it known that I, JOHN A. STREUN, a citizen of the United States, residing at Bowie, in the county of Montague and State of Texas, have invented certain new and useful Improvements in Apparatus for Cleaning Cotton, of which the following is a specification.

My invention has relation to an improvement in boll breakers and cotton cleaners, and in such connection it relates more particularly to an arrangement and construction of instrumentalities so correlated that the cotton to be treated is subjected to a succession of picking, cleaning, beating and spreading operations, and then delivered to a breaker roll and breast prior to its delivery to a succession of instrumentalities correlated to again break the bolls and extract the cotton and then subject the cotton to a succession of beating and spreading operations prior to delivering it to the conveyer leading to the gin.

My invention comprises an apparatus wherein the cotton is delivered preferably under suction to the various instrumentalities and the cotton manipulated mechanically on or adjacent to a screen beneath which suction is applied if required to draw out the dirt loosened from the cotton during the successive mechanical manipulations.

In the carrying out of my invention I provide a succession of mechanical beaters and spreaders and pickers operating on a succession of screens, the instrumentalities serving to carry the cotton downward in a succession of steps to a breaker roll and breast. The cotton is then passed vertically through a revolving air pocket to a second breaker roll, screen and breast, and thereafter conveyed upward by a succession of mechanical pickers, beaters and spreaders operating on a succession of screens and finally discharged upon a belt conveyer or equivalent device leading to the gin.

The downwardly progressing mechanisms are separated by the screens from a source of air suction or vacuum device and when desired the upwardly progressing mechanisms are likewise separated by the screens from a suction apparatus or vacuum creating device.

The nature and scope of my invention will be more fully understood from the following description, taken in connection

with the accompanying drawings forming a part hereof, in which—

Figure 1 is a side elevational view of a boll breaker and cleaner embodying the main features of my invention. 60

Fig. 2 is an elevational view of the other side of the machine.

Fig. 3 is the top or plan view with the top or cover partly torn away.

Fig. 4 is a longitudinal sectional view of 65 the machine.

Fig. 5 is a top or plan view of a portion of the lower spreading picker rolls, and

Fig. 6 is a detail sectional view of the 70 boll breaker roll and breast, the section being taken on line 6—6 of Fig. 1.

Referring to the drawings, 1 represents the inlet flue or duct for cotton or cotton and bolls entering the machine. The cotton or bolls may be forced through inlet 1 by pressure of air or suction, and is discharged in front of one of a pair of beater rolls 2—2. Each roll 2 has its spokes or arms projecting radially and spirally from the center toward each end of the roll, and both rolls 80 revolve in the same direction which, as illustrated in Fig. 4, is clockwise. Each roll 2 revolves with its spokes just clearing a concave screen 3 and the axis of the front roll adjacent the inlet is in a plane above the 85 plane of the axis of the second beater roll 2. The first roll 2 catches the cotton and revolves it over and spreads it across the concave screen 3 and propels it onto operative engagement with the spokes or arms of the 90 second beater roll. This second beater roll in turn catches the cotton and revolves it over its screen, spreads it and propels it farther on in the chamber 4, within which all the upper beater, spreader and picker mechanisms of the machine are located. This chamber 4 has an outer or upper unperforated roof or casing 5, and a lower floor comprising a series of concave screens 3, each co-operating with a corresponding roll 100 or cylinder as hereinafter more fully described.

The next instrumentality in the chamber 4, succeeding the second beater roll 2, and revolving in a plane lower than the axis of 105 said roll 2, is a single beater wheel 6 having radiating arms which are parallel with each other and extend across the wheel 6 in parallel lines. The beater wheel catches the cotton as it leaves the second roll 2 and re- 110

volves it over its concave coöperating screen 3 and discharges the cotton to the first of a pair of picker rolls 7. Each picker roll 7 revolves over its coöperating screen 3 in the same direction as the wheels 6 and rolls 2, and the axis of the first picker roll 7 is below the axis of the wheel 6 and above the axis of the second picker roll. The first picker roll 7 catches the cotton from the beater wheel, revolves it over its screen 3 and delivers it to the second of the picker rolls 7. The last picker roll, after revolving the cotton over its screen 3, discharges it into a vertical extension 8, of chamber 4, and onto a boll breaker located in said extension 8. The boll breaker comprises a breaking roll 9 with parallel rows of teeth having pyramidal sharp edged backs 10, and rounded or semi-conical faces 11. The faces 11 co-act with the similar faces 12 of teeth arranged in parallel rows on the breaker breast 13. This breast is adjustable toward or away from the roll 9, being maintained under spring tension by means of the springs 14 coiled on bolts 15 and tending normally to press the breast 13 working in box 16.

The cotton, after passing between the roll 9 and breast 13, is discharged into a vacuum feeder 17, the revolving pockets of which discharge into the lower part of extension 8 above the second breaker roll 18 and breast 19, which are practically duplicates of the breaker roll 9 and breast 13.

The second roll 18 coöperates not only with its breast 19 but also with a concave screen 20, over which it draws the cotton after crushing the bolls against the breast 19.

The cotton, after being drawn by picker roll 18 over screen 20, is delivered to the first of a set of three spreading and beating rolls 21, 22 and 23. Each spreading and beating roll revolves in the same direction as breaking rolls 9 and 18, and in a direction opposite to that in which picker rolls 7 revolve. The axis of roll 21 is below the axis of roll 22, and the axis of roll 23 is above that of roll 22.

The prongs or fingers on each roll 21, 22 and 23 are arranged in double spirals starting from the middle and working therefrom to each end. (See Fig. 5). The arrangement of these spirals on roll 21 corresponds with that of the spirals on roll 23, but the spirals of roll 22 are arranged reversely to the spirals of roll 21 or roll 23. The spiral fingers of roll 21 or 23 work the cotton from the center toward the ends of the roll 21 or 23, but the spiral fingers of roll 22 work the cotton from the ends of roll 22 toward its center. This combined beating and spreading of the cotton by beater rolls is broadly new with me.

Each roll 21, 22 or 23 revolves over a concave screen 20, and the last roll 23 in series

delivers the cotton to a picker roll 24 of substantially the same construction as picker rolls 7. This picker roll 24 revolves the cotton over a concave screen 20 and then discharges the same through outlet 25 from chamber 26, in which breaker roll 18, spreading beater rolls 21, 22 and 23, and picker roll 24 all revolve. The outlet 25 leads preferably to a belt distributor 27.

The space below the screens 3 is partitioned off from the vertical extension 8 and chamber 26 by an unperforated and preferably V-shaped partition 28. In the base of the chamber 29 so formed is located a trash conveyer 30 of screw type discharging into a flue 31 leading to the exterior of the machine. The discharge end of the flue 31 is normally closed against entrance of external air by the canvas valve 32.

The chamber 29 below screens 3 is in open communication by ports 33 with a duct 34 leading to a suction apparatus. The combined areas of ports 33 is equal, or approximately so, to the cross sectional area of the duct.

The space below the lower concave screens 20 has inclined walls 35 to lead the dirt or trash coming through screens 20 to a vacuum pocket 36 discharging to the exterior of the machine. The chamber 37 below screens 20 is preferably connected through ports 38 with a duct 39, tapping the suction duct 34.

The inlet 1 is connected by a passageway 40, having an inner screen wall 41, and an outer unperforated wall 42, directly with the belt distributor 27. A valve or damper 43 in inlet 1 may be turned to dotted position (see Fig. 4) to close the inlet of cotton to the machine and conduct the cotton directly to passageway 40. A valve or damper 44 in passageway 40, when in dotted position, closes the outlet 25 from chamber 26 and opens the passageway to the distributor 27.

By this manipulation of dampers 43 and 44 the cotton from inlet 1 may be diverted when required from the boll breaking and cleaning instrumentalities and discharged directly upon the belt distributor.

In the operation of my machine the cotton for inlet 1 is manipulated by a succession of instrumentalities over the screens 3 in a step by step downward and rotary movement of the cotton. The beater rolls 2, and beater wheel 6 thoroughly beat up and fluff the cotton and carry it over and across the respective screens 3. When suction is applied to chamber 29 the dirt loosened from the cotton by the vibrating and combing operations of rolls 2 and wheel 6 is sucked through the screens 3 to the trash conveyer 30 in said chamber 29. The picker rolls 7 further manipulate the cotton over the coöperating screens 3 before the cotton reaches the first breaker mechanism. Should the cotton be

free from bolls, the upper or lower, or both upper and lower, breaker rolls 9 and 18 may be rendered practically inoperative by extracting a breast or both breasts 13 and 19. 5 The cotton is next taken up by the rolls 21, 22 and 23, and not only revolved and beaten, but is moved laterally over the coöperating screens 20 toward and away from the ends of the rolls. Suction when applied to chamber 37 below screens 20 serves to draw the loosened dirt from the cotton, in its passage through the rolls 21, 22 and 23. The final picking operation performed by the picker roll 24 serves to loosen the cotton and dis- 10 tribute it in proper condition upon the conveyer 27.

My machine is compactly built and is most admirably adapted for cleaning bolly or damp cotton since the impure or dirty cotton is rolled and shifted and picked and beaten up by a succession of mechanical instrumentalities and is tumbled down and drawn up step by step to receive the proper aeration and proper fluffing prior to its dis- 15 charge to the conveyer 27.

The peculiar formation of the teeth on breaker rolls 9 and 18 insures the proper manipulation of the staple to remove the burs or bolls without chopping or breaking 20 the cotton, and hence such formation of the teeth forms a desirable portion of the present invention.

Having thus described the nature and objects of my invention, what I claim as new 25 and desire to secure by Letters Patent, is:—

1. In an apparatus of the character described a plurality of beating and spreading rolls, each roll provided with double spiral rows of fingers and each row extending from 30 a point intermediate of the ends of the roll and extending therefrom to the ends of the roll.

2. In an apparatus of the character described a plurality of beater and spreading 45 rolls having their axes arranged one below the other and each roll provided with double spiral rows of fingers, and each row extending from the center toward the respective ends of the roll, combined with a plurality of 50 concave screens each coöperating with a beater and spreading roll.

3. In an apparatus of the character de-

scribed, a downwardly inclined chamber under suction, an extension leading vertically from said chamber and a second upwardly 55 extending chamber under suction, combined with beating and spreading rolls, and picker rolls arranged in step like order in the downwardly extending chamber, a boll breaking mechanism arranged in the vertical extension, beating and spreading rolls and a picker roll mechanism arranged in step like order in the upwardly extending chamber and a series of concave screens in each chamber and each coöperating with a respective 60 roll and mechanism.

4. In an apparatus of the character described, a downwardly inclined cleaning chamber, a series of concave screens forming the floor of said chamber, a series of cleaning instrumentalities arranged in step by step order in said chamber, each instrumentality coöperating with a screen, a means for creating suction below said screens, a vertical extension leading from said chamber, 70 a boll breaking mechanism arranged in said extension, an upwardly inclined chamber leading from the bottom of said extension, a series of concave screens forming the floor of said second chamber, a series of cleaning 75 instrumentalities comprising essentially three rolls each provided with double spiral rows of fingers and each row beginning at a point intermediate of and extending to the ends of the roll, said instrumentalities arranged in 80 step by step order in said second chamber, each instrumentality coöperating with a screen, and a means for creating suction below the screens of said second chamber.

5. In an apparatus of the character described, a boll breaker roll and breast, each provided with rows of teeth having semi-conical operative front faces and semi-pyramidal rear faces.

6. In an apparatus of the character de- 95 scribed, a boll breaker roll and breast, each provided with rows of teeth having semi-conical operative front faces and semi-pyramidal rear faces, in combination with a concave screen coöperating with said roll. 100

In testimony whereof I have signed my name to this specification.

JNO. ARNOLD STREUN.
